HAIR CURLING DEVICE

Rocco Pezzella, Washington, D. C.

Application January 11, 1934, Serial No. 706,278

12 Claims. (Cl. 132—33)

The object of the present invention is to provide a simple and convenient means for wrapping hair as a preliminary to the treatment thereof to curl it, the means being peculiarly effective in securing smoothness of the convolutions as well as tightness on the mandrel.

An embodiment of the invention is illustrated in the accompanying drawing, wherein:

Figure 1 is a side elevation showing the device 10 in place on the head and with a lock of hair wrapped thereon.

Figure 2 is a top plan view of the mechanism.

Figure 3 is an end elevation of the same.

Figure 4 is a cross sectional view on the line 15 4—4 of Figure 1.

In the embodiment disclosed, a frame is employed, comprising an elongated bar 5 with upstanding heads 6 at its ends. The free ends of these heads carry offset arms 7 that terminate in ears 8. Pivotedly mounted on ears 9 that outstand from one end of the bar 5 is a clamping bar 10 that extends longitudinally of the bar 5 and has its free end bifurcated as shown at 11. A clamping bolt 12, pivoted to the other end of the bar 5, is adapted to enter the bifurcation 11; this clamping bolt, including a nut 13 threaded thereon and arranged to overlie the free end of the clamping bar 10.

A mandrel 14 is journaled in the heads 6 and extends longitudinally of the frame bar 5 and the clamping bar 10 at one side of the same. It is provided with a suitable "key" handle 15 by which it may be rotated. Pivoted to the ears 8 of the arms 7 are other arms 16 that overlie the arms 7 and terminate in downwardly turned hooks 17. These hooks constitute journal boxes for the gudgeons 18 of a pressure roller 19 that bears upon the mandrel 14. This roller 19 may be of yielding material. In order to secure yielding pressure of the roller 19 on the mandrel 14, stems 20 may be pivoted, as illustrated at 21, to the arms 7 and detachably passed through notches 22 in the arms 16. Coiled springs 23 on the free end portions of the stems 20 are adapted to bear upon the arm 16 and their tension can be regulated by nuts 24 threaded on the stems. If desired the pressure roller 19 may be positively rotated by the mandrel 14 through the medium of intermeshing gears 25 carried respectively by

50 these parts. However, it is possible that the pressure roller may be caused to turn by frictional contact with the mandrel 14, or the hair wrapped thereupon. If the gears 25 are employed they may be covered by shields 26. In order to prevent the roller 14 turning rearwardly

and loosening the hair wrapped thereon, a holding dog 27 may be employed that may be engaged with one of the gears 25 located on the roller 14.

It is believed the manner of using the device will be clear by reference to Figures 1 and 4. The frame bar 5 is placed upon the hair at the scalp and the base of a lock of hair to be wrapped on the mandrel is clamped between and by the clamping bar 10 and the frame bar 5. This can be readily accomplished as the bar 10 can be 10 swung to open position as indicated in Figure 2, if the nut 13 is screwed toward the outer end of the bolt 12 and the bolt swung out of the bifurcation of the clamping bar. After the lock is placed the bar 10 is swung back against the same, the clamping bolt placed in position and the nut threaded down upon the bar 10. The end of the lock is placed between the mandrel 14 and the pressure roller 19, whereupon by turning the handle 15, the mandrel and roller will be rotated and the lock will be wrapped tightly and smoothly upon the mandrel. If desired the lock may be divided and part of the hair wrapped in opposite directions as indicated in Figure 1. Or obviously it may be wrapped all at one side of the base of the lock. When the lock has been wrapped the arms 16 may be released by swinging the stems 20 and the parts carried by them to disengaged relation with respect to the arms 16, whereupon the arms may be swung outwardly and the pressure roller removed. This leaves the mandrel with the hair thereon exposed to the further usual treatments well known in the art and therefore unnecessary to here explain.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim is:

1. A hair curling device comprising a frame, a rotatable mandrel journaled on the frame and on which the hair is wrapped, and a pressure roller cooperating with the mandrel and journaled on the frame, said roller pressing against the hair wrapped upon the mandrel.

2. A hair curling device comprising a frame, a rotatable mandrel journaled on the frame and on which the hair is wrapped, and a pressure roller cooperating with the mandrel and journaled on the frame, said roller pressing against the hair

- wrapped upon the mandrel, said mandrel and roller being separable.
3. A hair curling device comprising a frame, a rotatable mandrel journaled on the frame and on which the hair is wrapped, and a pressure roller cooperating with the mandrel and journaled on the frame, said roller pressing against the hair wrapped upon the mandrel, said mandrel and roller being separable and one being removable from the frame.
4. A hair curling device comprising a frame, arms movably mounted on the frame, a rotatable mandrel on which the hair is wrapped and a rotatable pressure roller coacting with the mandrel to press the hair on the mandrel as the mandrel is rotated, one being journaled on the frame and the other journaled on the arms, and means by which one may be rotated.
5. A hair curling device comprising a frame, arms movably mounted on the frame, a rotatable mandrel on which the hair is wrapped and a rotatable pressure roller coacting with the mandrel to press the hair on the mandrel as the mandrel is rotated, one being journaled on the frame and the other journaled on the arms, means by which one may be rotated, and gearing connecting the mandrel and roller to effect their simultaneous rotation.
6. A hair curling device comprising a frame, a rotatable mandrel on which the hair is wrapped, journaled on the frame, a clamp for the base of the hair mounted on the frame alongside the mandrel, and a pressure roller detachably journaled on the frame and cooperating with the mandrel to press the hair on the mandrel as the mandrel is rotated.
7. A hair curling device comprising a frame having an elongated frame bar, a clamp for the hair located longitudinally of the bar, a mandrel on which the hair is wrapped, journaled on the frame and located longitudinally of the bar and clamp, and a pressure roller detachably journaled on the frame and cooperating with the mandrel to press the hair on the mandrel as the mandrel is rotated.
8. A hair curling device comprising a frame having an elongated frame bar, a clamp for the hair located longitudinally of the bar, a mandrel on which the hair is wrapped, journaled on the frame and located longitudinally of the bar and clamp, and a pressure roller detachably journaled on the frame and cooperating with the mandrel to press the hair on the mandrel as the mandrel is rotated.
- on which the hair is wrapped, journaled on the frame and located longitudinally of the bar and clamp, and a pressure roller detachably journaled on the frame and cooperating with a side of the mandrel that is spaced from the clamp to press the hair on the mandrel as the mandrel is rotated.
9. A hair curling device comprising a frame, a mandrel rotatably mounted in the frame and on which the hair is wrapped, a clamp for the hair carried by the frame alongside the mandrel, and means on the frame for pressing the hair on the mandrel as the mandrel is rotated and the hair wrapped thereupon.
10. A hair curling device comprising a frame, a mandrel rotatably mounted on the frame and on which the hair is wrapped, a clamp for the hair carried by the frame alongside the mandrel, and means on the frame for pressing the hair on the mandrel as the mandrel is rotated and the hair wrapped thereupon, said pressing means being removable from the frame after the hair has been wrapped on the mandrel and secured by the clamp.
11. A hair curling device comprising a frame having a longitudinal bar provided with offset heads, a second bar pivoted to the frame bar and constituting therewith a hair clamping device, a mandrel rotatably mounted in the heads and located alongside the hair clamping bars, offset arms projecting from the heads, reversely disposed arms pivoted to the arms of the head, and a hair pressing roller journaled on the reversely disposed arms and coacting with the mandrel to press upon the hair as it is wrapped upon the mandrel by the rotation of said mandrel.
12. A hair curling device comprising a frame having a longitudinal bar provided with offset heads, a second bar pivoted to the frame bar and constituting therewith a hair clamping device, arms pivotally mounted adjacent the heads, a mandrel, and a hair pressing roller coacting with the mandrel, one being journaled on the heads, the other on the arms and said hair pressing roller pressing upon the hair wrapped upon the mandrel as said mandrel is rotated.

ROCCO PEZZELLA.
